D. L. BUTLER

BALL COCK

Filed May 4, 1927

Inventor

David L. Butler

By *Clarence O'Brien*
Attorney

UNITED STATES PATENT OFFICE.

DAVID L. BUTLER, OF BLACKFOOT, IDAHO.

BALL COCK.

Application filed May 4, 1927. Serial No. 188,759.

The present invention relates to improvements in ball cocks for use in flush tanks and has for its principal object to provide a structure which may be readily assembled or 5 disassembled and which will furthermore at all times be positive and efficient in its operation.

One of the important objects of the present invention is to provide a ball cock which 10 will eliminate the necessity of having to use the conventional thumb screws and the like such as are now generally used in ball cock structures now on the market. These thumb screws and the like are objectionable 15 in that the same will corrode and break off.

Furthermore by providing a ball cock structure such as is embodied in the present invention, the proper flow of the water through the intake pipe and the discharge of 20 the water therefrom into the flush tank can be more easily attained in a positive and efficient manner.

A further object is to provide a ball cock 25 of the above mentioned character which is simple in construction, inexpensive, strong and durable and further well adapted to the purpose for which it is designed.

Other objects and advantages of the invention will become apparent from the following 30 description taken in connection with the accompanying drawing.

In the accompanying drawing wherein like reference characters indicate corresponding parts throughout the same:

Figure 1 is a vertical sectional view 35 through the ball cock embodying my invention, and

Figure 2 is a top plan view showing the pivoted end of the float rod or lever and 40 supporting means therefor.

In the drawing wherein for the purpose of illustration is shown the preferred embodiment of my invention, the numeral 1 designates an enlarged supply pipe which 45 extends through a suitable opening provided therefor in the bottom of the flush tank, not shown, and has communication at its lower end with a source of water supply, not shown, in the conventional manner. This 50 pipe is threaded for receiving thereon the lock nut 2 whereby the same may be properly supported in the bottom of the flush tank.

This pipe or head 1 is formed at its upper 55 end with an internally threaded neck 3

which communicates with the top of the head or pipe 1 for receiving the lower externally threaded end of a vertically extending intake water pipe or tube 4 in the manner as clearly shown in Figure 1.

An internally threaded socket 5 is formed 60 on one side of the neck portion 3 of the head or pipe 1, and the upper face of the connection wall between the neck and the socket is inclined as shown at 6. The purpose of this socket is to provide a means for supporting and receiving the lower externally threaded end of an auxiliary intake pipe or tube 7. This pipe or tube 7 is formed with an inlet opening 8 which is 65 located adjacent the inclined upper face 6 of the connecting wall between the neck and the socket and this is clearly illustrated in Figure 1 of the drawing.

Surrounding the main intake pipe 4 is the 70 elongated tube or pipe 9 which is of a greater diameter than the outer diameter of the main intake pipe 4 and is spaced therefrom to provide an annular water outlet chamber 10. For the purpose of properly 75 spacing the outer pipe 9 with respect to the inner pipe 4, the outer pipe is formed with the inwardly projecting protuberances 11, in the manner clearly shown in the drawing, and the same are located adjacent the upper 80 and lower ends of the outer pipe. This outer pipe 9 extends from the upper end of the main intake pipe 4 to a point above the neck 3 so that the water which passes upwardly through the pipe 4 and is discharged 85 from the upper end thereof into the chamber 10 will pass into the flush tank, not shown, through the lower end of the outer pipe 9 for the purpose of refilling the flush tank.

The upper end of this outer pipe 9 is 90 externally threaded for receiving thereon the cap member 12 and the closed upper end 13 of this cap member is spaced from the upper end of the main intake pipe 4 and the outer pipe 9 to provide a chamber 14 in the 95 manner as also clearly shown in Figure 1.

Arranged within the chamber 14 is the 100 valve 15, the same being preferably formed from rubber and being in the form of a disc. This valve cooperates with the upper 105 discharge end of the main intake pipe 4 to close the same and prevent water from being discharged into the chamber 10 when the flush tank is filled to the proper height. A stem 16 extends upwardly from the central 110

portion of the disc valve 15 through a suitable opening provided therefor in the closed upper end 13 of the cap member 12. The upper end of this stem terminates in a hook 17.

A refill tube 18 extends from the outer side of the auxiliary intake pipe 7 at a point adjacent the upper end thereof, and is adapted to extend into the overflow pipe 10 of the flush valve (not shown) for the purpose well known in the art. A plug 19 is removably secured within the upper open end of the auxiliary intake pipe 7 and the upper portion of this plug is flattened or reduced as indicated at 20, and a shoulder 21 will be formed on each side of the flattened upper end portion 20 at its juncture with the plug 19. This shoulder is slightly inclined to provide means for supporting 15 the arms of the U-shaped member designated generally by the numeral 22. This U-shaped member has its arms 23 and 24 disposed on opposite sides of the flattened upper end portion 20 of the plug 19 and the 20 outer ends of these arms are disposed on opposite sides of the hook shaped upper end 17 of the stem 16 in the manner clearly shown in Figure 2.

A socket 25 is formed on the closed end of 30 this U-shaped member 22 for receiving one end of the float rod or lever 26 which carries on its outer end the hollow float 27.

A pin 28 extends through suitable registering slots provided therefor in the outer 35 end portions of the arms 23 and 24 of the U-shaped member 22 and the intermediate portion of this pin is disposed beneath the hook 17 for cooperation therewith in the manner clearly shown in the drawing.

40 The tube 9 is slidably supported over the main intake pipe 4 by reason of the cap 12 and the hook and pin connection described above so that said pipe 9 will move vertically on the pipe 4 simultaneously with the cap 45 in a manner readily obvious from the construction shown.

The cap 12 is connected on the upper end of the slidable tube 9 whereby to provide a unitary structure and the disc valve 50 15 is held against the under side of the top of the cap due to the weight of the slidable tube and said cap and furthermore the tube 9 is maintained in a raised position so that the disc valve is out of engagement with the 55 upper end of the main intake pipe by the weight of the float carrying member when the water in the flush tank is at a predetermined level, and manifestly when this float carrying member rises, the pivoted end 60 of said member will move downwardly to effect a downward sliding movement of the tube 9 on the pipe 4 so that the disc valve will be brought into engagement with the upper end of the main intake pipe.

65 Also forming an important part of the

present invention is the piece of wire 29, the intermediate portion of which is disposed alongside of one of the arms of the U-shaped member 22 adjacent the base portion thereof. The inner end of this piece of wire is disposed laterally through suitable registering openings provided therefor in the intermediate portions of the arms 23 and 24 of the U-shaped member 22, and a registering opening in the flattened upper end portion 20 of the plug 19 whereby to provide a fulcrum for the float rod and the float carried thereby. This fulcrum is designated by the numeral 30, and as clearly shown in Figure 2 of the drawing. The other end of the wire is also disposed laterally in the same direction as the fulcrum forming portion 30 and extends across the rear portion of the U-shaped member 22 and is then disposed downwardly and thence 70 inwardly whereby to form a spring lip 31 which normally bears against the rear end or socket 25 of the U-shaped member.

The operation of my improved ball cock may be briefly stated as follows:

With the parts arranged as shown in Figure 1 of the drawing, the valve 15 is raised out of engagement with the upper end of the main intake pipe 4 and water will flow upwardly through the pipe 4 and will be 95 discharged out through the upper end thereof into the chamber 14 then into the chamber 10 where the water will flow into the flush tank and a certain quantity of the water in the flush tank will enter the inlet opening 8 100 formed in the lower end of the auxiliary intake pipe 7 and pass upwardly therethrough and will be discharged out through the refill pipe 18 into the upper portion of the flush tank, not shown.

105 As the flush tank becomes filled, the float 27 will rise upwardly in the conventional manner and the U-shaped member 22 will swing on its fulcrum 30 and as the outer ends of the arms of the U-shaped member 110 are operatively connected to the stem of the valve, said valve will be moved downwardly into engagement with the upper discharge end of the main intake pipe 4, thus cutting off the water from entering the 115 chamber 10.

When the water in the flush tank is empty, the float will descend and consequently swing the outer ends of the arms of the U-shaped member 22 upwardly thus 120 raising the valve to an open position whereby water will again be permitted to flow downwardly through the chamber 10 for the purpose of refilling the flush tank.

125 It will thus be seen from the foregoing description that I have provided a ball cock for flush tanks which will at all times be positive and efficient in its operation, and furthermore the simplicity of my device enables the part to be readily and easily ac- 130

cessible and the device may be quickly assembled or disassembled without any difficulty.

The present ball cock will insure the delivery of the water to the proper place, and there will be no possibility of any water striking the top of the lid of the tanks as frequently happens with the type of ball cocks now generally in use.

10 A ball cock constructed in accordance with the present invention may be manufactured at a very low cost and will also be strong and durable.

15 While I have shown the preferred embodiment of my invention, it is to be understood that various changes in the size, shape and arrangement of parts may be resorted to without departing from the spirit of the invention and the scope of the appended claims.

Having thus described the invention, what I claim is:—

1. In a ball cock, a supply head, a main intake pipe supported at its lower end on said head and communicating therewith, an auxiliary intake pipe supported on the head and being out of communication with the head, said auxiliary intake pipe being provided with a water inlet opening in the lower portion of the side thereof, a tube surrounding the main intake pipe and being spaced therefrom to provide an annular water outlet chamber, the lower end of the tube being spaced from the lower end of the main intake pipe whereby a quantity of water discharged from the chamber will enter the auxiliary intake pipe through the inlet opening formed therein, a cap secured on the upper end of the tube, the closed end of the cap being spaced from the upper outlet end of the main intake pipe, a valve arranged within the cap for cooperation with the upper discharge end of the main intake pipe, a plug secured in the upper end of the auxiliary intake pipe, a refill pipe extending from the upper portion of the auxiliary intake pipe, a float carrying member pivotally supported on said plug, and cooperating means between the free end of the pivoted member and the valve for moving the valve into or out of engagement with the upper end of the main intake pipe.

2. In a ball cock, a supply head, a main intake pipe supported at its lower end on said head and communicating therewith, an auxiliary intake pipe supported on the head and being out of communication with the head, said auxiliary intake pipe being provided with a water inlet opening in the lower portion of the side thereof, a tube surrounding the main intake pipe and being spaced therefrom to provide an annular water outlet chamber, the lower end of the tube being spaced from the lower end of the main intake pipe whereby a quantity of

water discharged from the chamber will enter the auxiliary intake pipe through the inlet opening formed therein, a cap secured on the upper end of the tube, the closed end of the cap being spaced from the upper outlet end of the main intake pipe, a valve arranged within the cap for cooperation with the upper discharge end of the main intake pipe, a plug secured in the upper end of the auxiliary intake pipe, a refill pipe extending from the upper portion of the auxiliary intake pipe, a float carrying member pivotally supported on said plug, and cooperating means between the free end of the pivoted member and the valve for moving the valve into or out of engagement with the upper end of the main intake pipe, said last mentioned means comprising a stem extending upwardly from the valve through the closed end of the cap, a hook formed on the upper end of the stem, and a laterally projecting pin carried by the pivoted member for engagement with said hook.

3. In a ball cock, a supply head, a main intake pipe supported at its lower end on said head and communicating therewith, an auxiliary intake pipe supported on the head and being out of communication with the head, said auxiliary intake pipe being provided with a water inlet opening in the lower portion of the side thereof, a tube surrounding the main intake pipe and being spaced therefrom to provide an annular water outlet chamber, the lower end of the tube being spaced from the lower end of the main intake pipe whereby a quantity of water discharged from the chamber will enter the auxiliary intake pipe through the inlet opening formed therein, a cap secured on the upper end of the tube, the closed end of the cap being spaced from the upper outlet end of the main intake pipe, a valve arranged within the cap for cooperation with the upper discharge end of the main intake pipe, a plug secured in the upper end of the auxiliary intake pipe, a refill pipe extending from the upper portion of the auxiliary intake pipe, a substantially U-shaped member, a float rod securing socket carried by the closed end of the U-shaped member, the arms of the U-shaped member straddling said plug, a fulcrum forming pin extending through the arms and through said plug, and cooperating means between the free ends of the arms of the U-shaped member and the valve for moving the same into or out of engagement with the closed upper outlet end of the main intake pipe.

4. In a ball cock, a supply head, a main intake pipe supported at its lower end on said head and communicating therewith, an auxiliary intake pipe supported on the head and being out of communication with the head, said auxiliary intake pipe being provided with a water inlet opening in the low- 130

er portion of the side thereof, a tube surrounding the main intake pipe and being spaced therefrom to provide an annular water outlet chamber, the lower end of the tube being spaced from the lower end of the main intake pipe whereby a quantity of water discharged from the chamber will enter the auxiliary intake pipe through the inlet opening formed therein, a cap secured 10 on the upper end of the tube, the closed end of the cap being spaced from the upper outlet end of the main intake pipe, a valve arranged within the cap for cooperation with the upper discharge end of the main intake 15 pipe, a plug secured in the upper end of the auxiliary intake pipe, a refill pipe extending from the upper portion of the auxiliary intake pipe; a substantially U-shaped member; a float rod securing socket carried by the 20 closed end of the U-shaped member, the arms of the U-shaped member straddling said plug, a fulcrum forming pin extending through the arms and through said plug, cooperating means between the free ends 25 of the arms of the U-shaped member and the valve for moving the same into or out of engagement with the closed upper outlet end of the main intake pipe, said last mentioned means comprising a stem extend-

ing upwardly from the valve, a hook formed 30 on the upper end of the stem and disposed outwardly of the cap, and a pin extending transversely between the outer ends of the arms of the U-shaped member, said hook being disposed between the outer ends of the 35 arms and being in engagement with said pin.

5. In a ball cock, a water intake pipe, a vertically slideable tube surrounding the pipe and being spaced therefrom to provide a water outlet chamber, a cap secured on the 40 upper end of the slideable tube, the closed end of the cap being spaced above the upper outlet end of the intake pipe, a valve arranged within the cap for slideable movement therewith, a stem extending upwardly 45 from the valve and through the cap, a float carrying member operatively connected to the upper end of the stem for moving the valve into or out of engagement with the upper outlet end of the intake pipe, said 50 member comprising a lever pivotally supported intermediate its ends, the upper end of the stem being formed with a hook, and a pin extending laterally from one end of the lever and engaging the hooked upper 55 end of the stem.

In testimony whereof I affix my signature:
DAVID L. BUTLER.
